W. J. FLEEMAN

BURIAL CASE

Filed April 21, 1926

INVENTOR.

William J. Fleeman

BY

Geo. P. Kimmel. ATTORNEY.

UNITED STATES PATENT OFFICE.

WILLIAM J. FLEEMAN, OF ST. JOSEPH, MISSOURI.

BURIAL CASE.

Application filed April 21, 1926. Serial No. 103,560.

This invention relates to a shipping and burial case for caskets, and has for its object to provide, in a manner as hereinafter set forth, an air tight and water proof case of the class referred to for not only protecting a casket when shipped, but further for preserving caskets especially of the inexpensive and non-metallic types, when buried, whereby the use of expensive metallic caskets can be dispensed with and thereby affording persons of limited means to purchase comparatively inexpensive cases, in accordance with this invention, to preserve the caskets for their dead.

Further objects of the invention are to provide in a manner as hereinafter set forth, a case of the class referred to which is simple in its construction and arrangement, strong, durable, air tight, water proof, thoroughly efficient in its use, and comparatively inexpensive to manufacture.

With the foregoing and other objects in view, the invention consists of the novel construction, combination and arrangement of parts, as hereinafter more specifically described and illustrated in the accompanying drawing, wherein is shown an embodiment of the invention, but it is to be understood that changes, variations and modifications can be resorted to which fall within the scope of the claim hereunto appended.

In the drawings, wherein like reference characters denote corresponding parts throughout the several views:—

Figure 1 is a side elevation of a shipping and burial case in accordance with this invention.

Figure 2 is a top plan thereof partly broken away.

Figure 3 is a section on the line 3—3 of Figure 2.

A shipping and burial case in accordance with this invention, comprises a body portion in the form of an outer open top metallic casing referred to generally by the reference character 1, an inner open top non-metallic casing referred to generally by the reference character 2, an inner open top metallic casing referred to generally by the reference characters 3 and a top common to the said casings and referred to generally by the reference character 4. Each of said casings include a pair of sides, a pair of ends and a bottom. The casings are arranged in nested position.

The casing 1 is constructed of sheet metal

of the desired thickness, and each of the walls thereof as well as its bottom is inset and transversely corrugated to form a corrugated panel 5. Each panel is of less width and less length than its respective wall and so disposed whereby the wall will be surrounded throughout by a plane portion 6 of appropriate width and which projects outwardly from the panel 5. Each of the walls of the casing 1, at its upper end, is provided with an inwardly extending flange at the top thereoef. The flange of one wall merges into the flange of an adjacent wall whereby the flange is continuous at the top of the casing. The flange is formed with a horizontally disposed leg 7 and a depending vertically extending leg 8 at the inner end of the leg 7.

The intermediate casing 2 includes a pair of sides and a pair of end walls and a bottom. The walls of the casing 2 are constructed from wood and the latter is treated with creosote and tar to act as a preservative therefor. The casing 2, on its inner face and at its top is rabbeted throughout to provide a continuous ledge 9 and a vertically disposed abutment 10. The ledge 9, at its inner side, is cut away to form a seat 11. When the casing 2 is positioned in the casing 1, the leg 8 of the flange, formed at the top of the casing 1, is positioned against the abutment 10 and the leg 7 of the flange is positioned over and spaced from the top edge of the casing 2.

The inner casing 3 includes a pair of sides and a pair of end walls and a bottom. The sides and end walls of the casing 3, at the top thereof, are formed with outwardly extending right angular disposed flanges 12. The flange 12 of one wall merges into the flange 12 of an adjacent wall whereby the flange is continuous and which is mounted on the ledge 9 spaced above the seat 11, and engaged by the leg 8 formed at the top of the outside casing 1. The continuous flange at the top of the casing 3 is formed with spaced openings 13' for a purpose to be presently referred to. The sides and end walls and the bottom of the casing 3 are transversely corrugated throughout. The leg 8, in connection with the flange 12, provides a vertically disposed continuous abutment and a horizontally disposed seat at the top of the body portion and with said horizontally disposed seat positioned below the top edge of said body portion.

Owing to the manner of setting up the metallic casings 1 and 3, that is provided with corrugations, air spaces or channels provided between the non-metallic and the metallic casings so as to preserve the casing 2 as the latter is constructed from wood.

The top 4 consists of a wooden intermediate section 13, a corrugated metallic inner section 14 and a corrugated metallic outer section 15. The sections 14 and 15 are so constructed and arranged as to completely enclose the edges of the section 13. The top 4 corresponds in contour to the shape of either one of the casings, but it is of less length and of less width than the casing 1. The top 4 is of such size, when in closure position, as to have its edges snugly engage the leg 8 of the continuous flange formed at the top of the casing 1. The top 4 at its sides and ends is provided with vertical openings 16 which align with the openings 13' formed in the flange 12.

When the top 4 is mounted in closure position, it is not in contact with the flange 12, but it is mounted on a compressible gasket 16 positioned throughout the flange 12 and abutting against the leg 8 of the flange of the casing 1. The leg 8 of the flange of the casing 1 is seated on the flange 12 of the casing 3. The gasket 17 is formed from any suitable resilient material, such as rubber, is substantially co-extensive with the flange 12, and is formed with spaced openings 19 which align with the openings 13' and 16.

The seat 11 provides a clearance for the heads 19 of rows of vertically extending bolts 20 which project through the openings 13', 18 and 16 and further extend a substantial distance above the cover 4. The bolts 20 are coupled with the intermediate casing 2 by the flange 12 of the inner casing 3. The heads of the bolts 20 are mounted against the seat 11 and which is overlapped by the flange 12 of the casing 3. Carried on the upper ends of the bolts 20 are butterfly nuts 21 for clamping the top 4 in closure position as well as for compressing the gasket 17 to provide an air tight seal. The butterfly nuts 21 when removed from the bolts 20 will allow of the top 4 to be removed from closure position.

The top 4 has secured to the upper face thereof a rectangular reinforcing member 22 constructed from an intermediate portion 23 of wood, an inner metallic portion 24 and an outer metallic portion 25. The metallic portions of the member 22 are transversely corrugated and are so constructed and arranged to completely enclose the edges of the intermediate wooden portion 23. The reinforcing member 22 is fixedly secured to the upper face of the top 4 in any suitable manner, and has each end provided with a pair of hand grips 26, to permit of the convenient removal of the top 4 from closure

position, when the nuts 21 are removed from the upper ends of the bolts 20.

Arranged at each side of the casing 1 is a series of spaced handles 27 and positioned against each end of the casing 1 is a handle 28. The handles 27 and 28 are fixedly secured in position by hold fast devices 29 which extend through the casings 1, 2 and 3 and are secured in anchoring members 30 arranged against the inner face of the inner casing 3.

Preferably the inner and outer metallic casings are transversely corrugated, but it is to be understood they can be of other contour. Preferably the intermediate casing is formed of wood, but it can be set up from any other non-metallic material, such as sheet rock, cletox, corrugated paper, cork, wood pulp or compressed vegetable.

It is to be understood that a composite sectional body portion, in accordance with this invention, is applicable for use other than solely to a combined shipping and burial case, for example various forms of receptacles, containers or storage compartments.

A burial case in accordance with this invention will not only protect a casket when shipped, but will further preserve an inexpensive and non-metallic casket, when buried, under such conditions disposing with the use of expensive metallic caskets and thereby afford persons of limited means to preserve inexpensive caskets for their dead, and thereby it is thought the many advantages of a burial case, in accordance with this invention, can be readily understood, particularly in view of the fact that it is air tight and water proof, and although the preferred embodiment of the invention is as illustrated and described, yet it is understood that advantages in the details of construction can be had which will fall within the scope of the invention as claimed.

What I claim is:—

A burial casket comprising nested outer, inner and intermediate container sections each including a bottom and a pair of side and a pair of end walls, said inner and outer sections formed of metallic material and said intermediate section non-metallic, the walls and bottom of the outer section having an inset corrugated portion, the side and end walls of said inner section corrugated throughout, said outer and inner sections of greater height than the walls of the intermediate section and extending above and overlapping the top edge of the latter, the overlapping parts of said inner and outer sections co-relating to provide a seat for a cover element at the upper end of the container below the top of said outer section.

In testimony whereof, I hereunto affix my signature.

WILLIAM J. FLEEMAN.
